JULES J. BRELL, OF NEW YORK, N. Y., ASSIGNOR OF ONE-THIRD TO HARRY RADZINSKY,
OF NEW YORK, N. Y.

TUB COVER

Application filed April 9, 1932. Serial No. 604,146.

This invention relates to a cover member or shield for use upon wooden tubs and like receptacles of the kind in general use for containing butter, lard and like products. Tub⁵s of this kind are usually found in grocery stores, dairies and the like, where they are displayed by being supported in a display cabinet, the tub being held on its side so that the open top of the tub is disposed towards the front of the cabinet. To remove the butter or tub contents in such quantities as sold, the door of the cabinet is opened and the grocer reaches in the tub and cuts away the required amount of butter or other material from that in the tub. The butter removed from the tub is usually carried to a scale where it is weighed. In removing the butter from the tub in the manner described it often happens that pieces of butter fall from the knife and drop down between the end of the tub and the front of the cabinet. This not only causes waste of the butter but also requires constant removal of the tub to enable the dropped butter to be removed and the cabinet cleaned. Tub²⁰s displayed in the manner indicated do not present a very satisfactory appearance while located in the cabinets.

The object of this invention, therefore, is to provide a cover or shield for tubs of the kind described to not only enhance the appearance of the displayed tub, but also to prevent waste of the tub contents.

The device is preferably in the form of a metal annulus and it removably seats on the edge or top of the tub. The cover or shield contemplated by this invention is provided with a projecting plate or catch-member which serves to catch and retain any particles of butter or other merchandise, which are dropped from the grocer's knife while removing it from the tub. The improved cover or shield is arranged to be detachably secured to the tub and is instantly removable therefrom for application to a filled tub, when a tub is emptied of its contents.

In the accompanying drawing, wherein the preferred embodiment of my invention is shown, Fig. 1 is a front elevation of a cover or shield made in accordance with this inven-

tion; Fig. 2 is a side elevation of a butter tub or like receptacle, with the cover or shield fitted in position on it; Fig. 3 is a sectional view on the line 3—3 of Fig. 2, looking in the direction of the arrows; and Fig. 4 is a perspective view of one of the hooks which fits over the bottom edge of the tub and which, in co-operation with springs, serves to hold the cover or shield removably in place on the tub.

My improved cover or shield consists of a metal annulus which seats upon or against the upper edge 17 of a butter tub 15 or other like receptacle. The annulus is provided with an inwardly directed flange 7 which rests against the edge 17 of the tub and conceals it from view. A laterally extending flange 6 is formed on the annulus and projects from the side of the tub when the annulus is fitted in place. An arcuate plate 16 is secured to the cover as shown in the drawing, the plate being disposed at the bottom of the cover as clearly shown in Fig. 2 when the cover is in place and it extends partly about the same to form a catch-member for butter dropped from the knife when removing it from the tub. The flange 6 is provided with spaced holes 9 which are engaged by the ends of springs 10. There are two pairs of springs and each pair has its ends engaged by a loop 14 formed as part of a hook member 11. This member 11 is shown as being bent from a section of wire and it is provided with spaced parallel leg portions 12, the ends of which are curled or bent to form hooks 13. Two of the springs 10 are located at each side of the annulus 5 and two hook members such as shown at 11 are employed.

In Figs. 2 and 3 the device is shown as applied to a wooden butter tub or similar receptacle 15. The cover 5 fits snugly on the upper edge 17 of the tub, with the flange 7 abutting against the edge 17 and the lateral flange 16 extending laterally from the outer face of the tub. When the cover member is in position it will be seen that the same wholly covers and hides the relatively rough edge of the tub from view. The hook members 11 are drawn back toward the end or bottom of the tub and the hooks 13 are fitted over

the rear edge of the tub as clearly shown in Figs. 2 and 3. The tension of the springs is such as to securely hold the cover member on the top edge 17 of the tub. To prevent the 5 tub from rolling or shifting when resting on its side, as indicated in Fig. 2, it may be found desirable to provide a straight edge as at 8 on a portion of the flange 6. The tub in its position of display as shown in Fig. 2, 10 will rest, or be supported on, the part 8 of the flange 6 and will be thereby prevented from rolling or shifting.

With the member 5 in position it will be seen that the front of a butter tub presents 15 the appearance of being enclosed or encased in an ornamental metallic ring. When the grocer removes the butter from the tub, any particles of the butter falling from his knife will be caught by the plate 16 from which 20 they may be easily removed.

What I claim is:—

1. A cover for the edge of tubs and like receptacles comprising a ring adapted to fit 25 over the edge of a tub and conceal said edge, a shelf extending forwardly from the ring to catch dropped tub contents, and means extending rearwardly from the ring and resiliently engaging the rear end of the tub to hold the ring in position.

2. A cover for the edge of tubs and like receptacles comprising an annular ring adapted to seat on the edge of a tub and conceal said edge from view, an arcuate plate 35 extending from a portion of said ring and projecting forwardly from the same to form a catch-plate, springs extending rearwardly from the ring, said springs terminating in hooks which engage the rear edge of the tub to hold the ring in position.

3. A cover for the edge of tubs and like receptacles comprising an annular ring adapted to seat upon and conceal the edge of a tub, an arcuate plate extending from 45 a portion of said ring and projecting forwardly from the same to form a catch member, a plurality of springs attached to the ring and adapted to be drawn rearwardly toward the back of the tub, and hook members located on the ends of the springs for engagement with the rear of the tub to hold the ring in position.

4. A display device for tubs and like receptacles comprising a ring adapted to fit 55 over and conceal the edge of a tub, said ring being centrally open to permit access to the tub contents without requiring removal of the ring, a shelf extending about a part of said ring and projecting forwardly therefrom to form a catch-member for receiving dropped tub contents, and means for detachably holding the ring on the edge of the tub.

5. A device for the display of butter tubs 60 comprising a ring fitting against the edge of the tub and concealing the same while

the tub is resting on its side, said ring being open centrally so that access is had to the tub contents without removal of the ring, said ring having a straight edge portion to hold the tub on its side and preventing rolling of the tub when so held, an arcuate plate secured to the ring and extending forward to form a projecting shelf, and means for removably clamping the ring in position on the tub.

Signed at the city, county and State of New York, this 7th day of April, 1932.
